UNITED STATES PATENT OFFICE

96,639

DESIGN FOR A PYROPHORIC LIGHTER

Louis V. Aronson, Newark, N. J., assignor to Art Metal Works, Inc., a corporation of New Jersey

Application June 5, 1934, Serial No. 52,065

Term of patent 7 years

To all whom it may concern:

Be it known that I, Louis V. Aronson, a citizen of the United States, residing at Newark, in the county of Essex and State of New Jersey, have invented a new, original, and ornamental Design for a Pyrophoric Lighter, of which the following is a specification, reference being had to the accompanying drawing, forming part thereof, wherein:

Figure 1 is a front elevational view of the pyrophoric lighter;

Fig. 2 is a side elevational view of said pyrophoric lighter; and

Fig. 3 is a bottom view of said pyrophoric lighter.

I claim:

The ornamental design for a pyrophoric lighter substantially as shown.

LOUIS V. ARONSON.
